United States Patent

Des. 240,358
Patented June 29, 1976

240,358

FISHING LURE

Nay E. Cruise, Box 324, Cassville, Mo. 65625

Filed Oct. 20, 1975, Ser. No. 623,668

Term of patent 14 years

Int. Cl. D22—05

U.S. Cl. D22—27

Fig. 1.

Fig. 2.

Fig. 3.

Fig. 4.

Fig. 5.

Fig. 6.

FIG. 1 is a perspective view of a fishing lure embodying my new design;

FIG. 2 is a top plan view thereof;

FIG. 3 is a side elevational view thereof, the opposite side being of substantially the same appearance;

FIG. 4 is a bottom plan view thereof;

FIG. 5 is a front elevational view thereof; and

FIG. 6 is a rear elevational view thereof.

I claim:

The ornamental design for a fishing lure, as shown and described.
